UNITED STATES PATENT OFFICE.

LORENZO B. NORTON, OF NEW HAVEN, CONNECTICUT.

REED-ORGAN.

SPECIFICATION forming part of Letters Patent No. 270,974, dated January 23, 1883.

Application filed April 14, 1882. (No model.)

To all whom it may concern:

Be it known that I, LORENZO B. NORTON, a citizen of the United States, residing at New Haven, in the county of New Haven and State 5 of Connecticut, have invented certain new and useful Improvements in Reed-Organs, of which the following is a specification, reference being had therein to the accompanying drawings, in which—

10 Figure 1 is a plan view of a portion of the action of a reed-organ. Fig. 2 is a front elevation of a portion of the action. Fig. 3 is a view of one end of the action, the end block being omitted to show the several parts. Fig. 15 4 is a rear elevation of a portion of the action. Fig. 5 is a view of the under side of the wind-chest; and Fig. 6 is a view of a detached part, to be hereinafter described.

My invention relates to reed-organs, its object being to increase the volume and variety 20 of tone.

To this end the improvement consists in the arrangement and construction of parts, as hereinafter more fully described and claimed.

25 To enable others to make and use my improvement, I will describe it in detail and its mode of operation.

The reed-frames A, in which the ordinary sets of reeds are placed, are fastened on the 30 wind-chest F, and are shown in Figs. 2, 3, and 4. The parts usually attached to these frames—as the mutes m and swell n—are shown in Fig. 3. The frame B, Figs. 2 and 3, in which an extra set of reeds is placed, is hinged to the 35 key-frame D. A cloth, a, Fig. 3, extends around the reed-frame B, is cemented to it and also to the key-frame D. The cloth allows the side of the reed-frame remote from the hinge to rise and fall, and with the reed and key 40 frames incloses the reeds. The piece b, Fig. 3, is attached to the feed-frame B, and forms a part of it. Holes are made through this piece, Figs. 1 and 3, in which the pitmen c move and operate the valves d, which are attached to the pitmen. To the front edge of the reed-frame, Fig. 2, pieces of cloth e are attached 45 and close the holes in which the reeds are placed. The piece of wood E, Fig. 6, is placed over the cloth pieces and is fastened to the 50 reed-frame. An end view of the piece E is

shown in Fig. 3 by broken lines, and the swell n' comes against its edge. The pitmen c are of such length that the keys operate them only when the reed-frame B is raised, and the rod g, levers h and i, Fig. 3, constitute the means 55 for raising it. The spring k, Fig. 3, connects the swells, so that as the lower swell is raised the upper swell is lowered, and the reverse. The key-frame D has the groove o, Fig. 3, on its under side, which extends the whole length 60 of the frame, and connects with the passage o', Fig. 2, in the end block leading to the wind-chest, a valve, x, Figs. 2 and 5, in the chest serving to open and close the passage. The reeds are placed in the reed-frame B with their 65 tongues on their under side.

Constructed as above described, the reed-frame B being raised, the air passes up through the valves d and through the groove o, and down through the passages o', there being a 70 passage in each end block into the wind-chest. With this construction no valves, x, are needed, the reeds being brought into action by raising the reed-frame B; but the construction may be varied. The reed-frame B may be 75 rigidly attached to the under side of the key frame, as frames are attached to the upper side of the wind-chest, and the rod g and levers h and i may be dispensed with. With this construction the reeds are brought into action by 80 opening the valves x by means of the stop s, Fig. 3, operating on the rod s', connected to the pivoted lever y. (Shown in Fig. 5.)

Having described my improvement and the mode of its operation, what I claim as new, 85 and desire to secure by Letters Patent, is—

The combination of the reed-frame A, wind-chest F, key-frame D, having groove o, end blocks E, provided with passages o', leading from said groove to the wind-chest, the reed-frame B, having a perforated frame, b, the pitmen c, contained in the frame b, and the valves d, and suitable connecting and operating mechanism, substantially as described.

In testimony whereof I affix my signature in 95 presence of two witnesses.

LORENZO B. NORTON.
